UNITED STATES PATENT OFFICE.

GABRIEL MUELLER, OF CINCINNATI, OHIO.

DESIGN FOR AN EMBLEM, FLAG, PENDANT OR ARTICLE OF SIMILAR NATURE.

53,045.

Specification for Design.

Patented Mar. 4, 1919.

Application filed August 23, 1918. Serial No. 251,200. Term of patent 14 years.

To all whom it may concern:

Be it known that I, GABRIEL MUELLER, a citizen of the United States, residing at Cincinnati, in the county of Hamilton and State of Ohio, have invented a new, original, and ornamental Design for Emblems, Flags, Pendants or Articles of Similar Nature, of which the following is a specification, reference being had to the accompanying drawing, forming part thereof.

The figure is a front view of an emblem, showing my new design.

I claim:

The ornamental design for an emblem, flag, pendant, or article of similar nature, substantially as shown.

GABRIEL MUELLER.
